[57] CLAIM

The ornamental design for athletic pants, as shown and described.

DESCRIPTION

FIG. 1 is a perspective view of athletic pants showing my new design in use, the broken lines showing a partial human form throughout the views being for illustrative purposes only and forming no part of the claimed design;

FIG. 2 is a front elevational view thereof;

FIG. 3 is a rear elevational view thereof; and,

FIG. 4 is a left side elevational view thereof, the right side being a mirror image.

FIG. 2

FIG. 1

FIG. 3
